(57) CLAIM

The ornamental design for a recessed heat sink with a discernible component as part of a device enclosure as shown and described.

DESCRIPTION

FIG. 1 is a front perspective view of a recessed heat sink with a discernible component as part of a device enclosure; FIG. 2 is a front corner perspective view of the recessed heat sink with a discernible component as part of a device enclosure;

FIG. 3 is a top view of the recessed heat sink with a discernible component as part of a device enclosure; FIG. 4 is a front view of the recessed heat sink with a discernible component as part of a device enclosure;

FIG. 7 is a right-side view of the recessed heat sink with a discernible component as part of a device enclosure; and, FIG. 8 is a bottom view of the recessed heat sink with a discernible component as part of a device enclosure.

The dashed broken lines depict boundaries; each dashed line and the area within form no part of the claimed design.
